UNITED STATES PATENT OFFICE

2,337,205

ELECTRICAL RELAY

Benjamin Mishelevich, Pittsburgh, Pa., assignor
to The Union Switch & Signal Company, Swiss-
vale, Pa., a corporation of Pennsylvania

Application July 23, 1942, Serial No. 452,072

11 Claims. (Cl. 280—93)

My invention relates to electrical relays, and has particular reference to relays of the flasher class arranged to operate contacts in such a manner as to open and close such contacts alternately. More particularly, my invention relates to a flasher relay of the pendulum type, such, for example, as is disclosed in Letters Patent of the United States No. 2,156,684, granted to Arthur W. Fisher and myself on May 2, 1939, for Electrical relays.

In a pendulum type flasher relay, two sets of contacts are operatively connected with the pendulum in such a manner that one set of contacts is closed in one portion of the pendulum stroke and the other set of contacts is closed in another portion of the stroke. Such a relay incorporates means for causing the pendulum to oscillate at substantially its natural period, thereby causing the contacts to become alternately opened and closed at a rate dependent upon the period of the pendulum.

In certain applications of such relays, as for example in the control of the lamps of flashing light signals at railway-highway intersections, it is desirable to close one set and open the other set of contacts when the relay is deenergized and the pendulum assumes its pendant or gravity biased position. This contact arrangement must be attained without producing a "limping" operation of the contacts, that is, the times during which the two sets of contacts are respectively opened and closed when the relay is energized should remain substantially equal. It has been proposed heretofore to provide means for obtaining the desired closure of contacts in the deenergized position of the relay while maintaining a substantially even time interval of operation of the two sets of contacts. Such means are shown, for example, in Letters Patent of the United States No. 2,156,685, granted on May 2, 1939, to Noble C. Shaw, which discloses means effective when the relay is deenergized for exerting a force on the pendulum to move it away from its gravity biased position to a position wherein one set of the two sets of contacts is closed. This patent also discloses means for exerting a force on the pendulum to resist movement of the pendulum during a portion of its stroke so as to shorten such portion of the stroke and thus to compensate for an unsymmetrical arrangement of the two sets of contacts operated by the pendulum.

An object of my invention is to provide novel and improved means for obtaining in a pendulum type flasher relay substantially equal time inter-

vals of operation of two sets of contacts, one set of which is closed in the deenergized condition of the relay.

Another object is to provide, in a relay of the class described, novel and improved means for obtaining substantially equal time intervals of operation of two sets of contacts which are arranged unsymmetrically so that one set is closed in the deenergized condition of the relay.

10 A further object is to provide a novel and improved pendulum combination having one moment of inertia in one portion of the stroke and having a different moment of inertia in another portion of the stroke.

15 An additional object is to provide novel and improved means for varying the time that a pendulum requires to swing through a portion of its stroke as compared to the time of the swing of the pendulum in another portion of the stroke.

20 A still further object is to provide novel and improved flasher relays of the pendulum type.

The above-mentioned and other important objects and characteristic features of my invention which will become readily apparent from the following description, are attained in accordance with the invention by providing in a flasher relay a pendulum combination comprising a pendulum and an auxiliary mass associated with the pendulum in such a manner as to provide two different resultant moments of inertia, one for each of two different portions of the stroke or cycle of the pendulum combination.

25 I shall describe two forms of apparatus embodying my invention, and shall then point out the novel features thereof in claims.

30 In the accompanying drawings, Fig. 1 is a view partially in front elevation and partially in section, showing one form of relay embodying my invention. Fig. 2 is a view partially in end elevation and partially in section, of the relay shown in Fig. 1. Fig. 3 is a top view showing in more detail the contact arrangement of the relay shown in Figs. 1 and 2. Fig. 4 is a view showing in more detail the pendulum combination, embodying my invention, of the relay shown in Figs. 1, 2 and 3. Figs. 5 and 6 show the pendulum combination of Fig. 4 in different operating positions. Figs. 7, 8 and 9 are views showing a modified form of the pendulum combination of Fig. 4, also embodying my invention, and adapted for use with the relay shown in Figs. 1, 2 and 3. In each of the several views, similar reference characters have been employed to designate corresponding parts.

35 Referring to the drawings, the reference char-

acter R designates as a whole a pendulum type flasher relay of the class shown for example in the aforesaid Patent No. 2,156,684. In view of the disclosure in this patent, only those portions of the relay essential to an understanding of my present invention will be described herein.

Relay R, in general, comprises an insulating top plate A from which is suspended by means of hangers 1 a suitable rectangular frame 2. A rockshaft 4 journaled at its ends in bearings 3 (see Fig. 3) suitably secured to frame 2, is biased to one position by a pendulum combination arranged to be oscillated at a predetermined frequency which depends upon the proportioning and adjustment of the parts, the oscillation being effected by means of a suitable motor device M hereinafter described.

The pendulum combination includes a compound pendulum which I shall term the main pendulum and which may have any suitable form but in the form here shown comprises a U-shaped bracket 7 having upwardly extending arms 7a pinned intermediate their ends to rockshaft 4 and provided at their upper ends with enlarged portions 7b to provide a desired mass for this portion of the pendulum. A depending threaded post 7c secured to the underside of yoke 7e of bracket 7 carries a counterweight 7f which is mounted eccentrically to the post 7c, and which serves both as a means for regulating the period of oscillation of the rockshaft within certain limits, and also as a means for varying the position to which the rockshaft is biased by means of the pendulum combination.

The pendulum combination also includes means operative to vary the resultant moment of inertia of the combination in certain portions of its stroke. These means comprise a movable mass so arranged that its center of gravity can be displaced from the rotational axis of the combination in one portion but not in another portion of the pendulum stroke, whereby to alter the moment of inertia or period of the pendulum combination in this one portion of the stroke.

In the form of the invention which is shown in Figs. 1 to 6, inclusive, this movable mass comprises an auxiliary pendulum 30 pivoted on a jackshaft 31 secured to one of the upwardly extending arms 7a at a point above the axis of rockshaft 4. The shafts 4 and 31 are arranged so as to be substantially in vertical alignment when the combination is at rest and assumes its gravity biased pendant position represented in Figs. 1 and 2. In this condition of the apparatus, the centers of mass of the main and auxiliary pendulums will lie very close to or within a common vertical axis.

A stop 32 is provided on leg 7a of the main pendulum and engages one side of the auxiliary pendulum 30 when the pendulum combination is in its gravity biased position. Stop 32 functions to prevent swinging movement of pendulum 30 to one side of the vertical axis of the combination while freely permitting the auxiliary pendulum to swing about its pivot to the other side of the vertical axis.

The previously referred to motor device M for oscillating the rockshaft 4 comprises an armature 8 which is pinned to the rockshaft at one side of bracket 7, and an electromagnet which cooperates with armature 8. This electromagnet may have any preferred construction, but in the form here shown comprises a winding 9 mounted on a backstrap 10 secured to the short arms 7a of two L-shaped pole pieces 11, the long arms

11b of which extend upwardly past the opposite sides of armature 8 and are secured to depending lugs 2b formed on frame 2. The angular disposition of armature 8 with respect to rockshaft 4 is such that, when the rockshaft occupies the position to which it is biased by the pendulum combination, the longer axis of the armature will be inclined from the vertical at an acute angle with a horizontal line joining the two pole pieces 11b, through the center of shaft 4, as best seen in Fig. 2. This acute angle may be varied through relatively wide limits, but I have found that the best operating characteristics are obtained for most conditions of operation when this angle is approximately 40°.

The relay also comprises a plurality of contacts, here shown as six in number and designated by the reference characters 12, 13, 14, 15, 16 and 17, respectively. These contacts are of the well-known mercury type, and each comprises (see Figs. 2 and 3) a pair of electrodes 18 and 19 disposed in an evacuated bulb containing a quantity of mercury 20 which flows into or out of engagement with the electrodes to make or break a circuit passing therethrough. Contacts 12, 13 and 14 are mounted in spring clips 21, 22 and 23, respectively, which are suitably secured to yoke 7e of bracket 7, and the contacts 15, 16 and 17 are mounted in spring clips 25, 26 and 27, respectively, which spring clips are likewise suitably secured to yoke 7e of bracket 7.

Certain of the contacts such, as for example, as the two contacts 12 and 15, may be employed to control the supply of energy to winding 9 of the motor device M in such a manner that winding 9 will be supplied with current when the contacts 12 and 15 are both closed, but when either one of these contacts becomes opened due to the motion of the rockshaft, the supply of current to winding 9 will be interrupted. This result is accomplished by a series connection of the two contacts 12 and 15. The position of rockshaft 4 at which the contacts 12 and 15 are adjusted to open will depend upon the angular position of the armature with respect to the rockshaft and on the proportioning of the parts, but when the armature is secured to the rockshaft in about the position shown, contact 15 will preferably be so adjusted that it will break the operating circuit when the rockshaft swings approximately 7° in a clockwise direction as viewed in Fig. 2 from the position to which it is biased. Also, contact 12 will preferably be so adjusted that it will break the operating circuit when the rockshaft swings approximately 10° in a counterclockwise direction as viewed in Fig. 2 from the position to which it is biased. It should be particularly pointed out, however, that satisfactory operation of the pendulum can be obtained with a variation of several degrees in either direction from the above described adjustment of the contacts 12 and 15. The remaining contacts 13, 14, 16 and 17 may be used for controlling the flashing lights of a highway crossing signal or other device, and are so adjusted that oscillation of the rockshaft with its intended amplitude will cause these contacts to become alternately opened and closed.

The operating mechanism of the relay is enclosed within a suitable casing 63 held in position against the underside of the top plate A by means of screws 65 which pass through clearance holes provided in the bottom of the casing, and are screwed into tapped holes pro-

vided in the lower ends of depending lugs 66, the upper ends of which are secured to the underside of frame 2.

The operation of the relay as a whole is as follows: When winding 9 of the electromagnet is deenergized, the rockshaft 4 will occupy the position to which it is biased by the pendulum combination and under these conditions the relay controlling contacts 12 and 15 will both be closed; one set or group, such as contacts 16 and 17, will also be closed while the other set, comprising contacts 13 and 14, will be opened. This arrangement is readily effected by suitably positioning the evacuated bulbs so that in the deenergized position of the armature, the terminals of the contacts 12, 15, 16 and 17 are bridged by the mercury therein while the terminals of contacts 13 and 14 are not so bridged. When, however, current is supplied to winding 9, a magnetic field is established between the pole pieces 11 of the electromagnet, which field causes armature 8 to turn in a clockwise direction as viewed in Fig. 2 in order to assume a position of minimum reluctance. This rotation of the armature will, of course, be transmitted to the rockshaft, and as soon as the rockshaft begins to rotate, contacts 13 and 14 will close and contacts 16 and 17 will open. During this portion of the stroke, the auxiliary pendulum 30 will swing away from its stop so that the two pendulums 7 and 30 swing in opposite directions with reference to their respective pivot axes. Winding 9 will become deenergized when pendulum 7 reaches the point at which contact 16 opens, and will thus remove the torque tending to rotate the armature, but the shaft and armature will continue to rotate beyond this position due to the acquired momentum of the parts. After this momentum is expended, however, the shaft will start to rotate in the opposite direction due to the action of gravity on the pendulum combination. The auxiliary pendulum will remain away from its stop 32 during this return portion of the clockwise stroke. As soon as the pendulum combination returns to the position in which contact 15 becomes reclosed, winding 9 will again become energized and will cause a retarding force to be exerted on the armature. This retarding force will be small, however, because the effective air gaps between the respective pole pieces and the armature will then be substantial and will be increasing rapidly. Just prior to the time that pendulum 7 reaches its normal pendant or biased position, contacts 13 and 14 will open and contacts 16 and 17 will close. When pendulum 7 swings past its normal pendant position, the auxiliary pendulum 30 will come to rest against stop 32 and will thus be carried with pendulum 7 during the remainder of the counterclockwise swing of the main pendulum. As soon as armature 8 is rotated to the position in which contact 12 opens, winding 9 will again become deenergized, and as a result, the rockshaft will continue to rotate in a counterclockwise direction due to the acquired momentum until it reaches a position at the end of its counterclockwise stroke, which position may be a few degrees less than the position reached at the end of the corresponding previous clockwise stroke. As soon as the energy of the pendulum has been spent in the counterclockwise direction, the action of gravity will cause a clockwise torque again to be exerted on the shaft, and as soon as the shaft is rotated in the clockwise direction to the position in which contact 12 closes, winding 9 will again become energized and will subse-

quently remain energized until the rockshaft has swung past its biased position to the position in which contact 15 opens. The energization of winding 9 during this portion of the movement will cause a pulse of energy to be exerted on the rockshaft which assists the clockwise rotation of the shaft, and the parts are so proportioned that this pulse at normal operating voltages will be sufficient to supply to the shaft the loss of energy during each cycle caused by friction and the retarding force on the magnet during the previous counterclockwise rotation of the rockshaft. It follows, therefore, that when the circuit of magnet 9 is closed, the rockshaft will oscillate at substantially the natural period of the pendulum combination as determined by the resultant moment of inertia of the main and auxiliary pendulums. This oscillation will cause the contacts 13, 14 and 16, 17 alternately to open and close in an obvious manner, and it will be apparent that by connecting these contacts in suitable control circuits they may be used alternately to energize and deenergize the flashing lights of a highway crossing signal of the well-known type, or to control any other apparatus requiring alternate energization and deenergization at a predetermined substantially constant frequency.

It should be noted that my invention provides novel and improved means for obtaining substantially equal intervals of operation of the two sets of asymmetrically arranged contacts. That is to say, a compound pendulum relay having one set of contacts normally closed and another set of contacts normally open in the pendant position of the pendulum, ordinarily will operate when the relay is energized to cause the normally closed set of contacts to be closed for a time interval greater than the time interval of closure of the normally open contacts. This is due to the fact that the contacts of the said one set are closed during the portion of the pendulum stroke that extends from one extreme position to a given point beyond the gravity biased intermediate position, while the contacts of the other set are closed in the portion of the pendulum stroke that extends from the other extreme position to the given point which is intermediate the said other extreme position and the gravity biased pendant position of the pendulum. It thus follows that the contacts of the two sets are closed throughout unequal portions of the pendulum stroke, hence if the pendulum combination operates at a constant frequency or rate, the contacts of the two sets will then be closed for unequal periods of time. This will result in a "limping" operation of the contacts. This uneven operation of the contacts is undesirable in many applications of the relay, particularly in the control of highway crossing signals and the pendulum combination which I have provided corrects this defect.

It will now be apparent that the combination of the two pendulums 7 and 30 is arranged so that when rockshaft 4 performs the counterclockwise portion of its stroke (as viewed in Fig. 2) from its normal biased position, the auxiliary pendulum 30 is carried along with pendulum 7 and the time interval required for the pendulum combination to travel from this position to its extreme counterclockwise position and back to the biased position is a function of the moment of inertia of the two pendulums considered as a unitary structure. Accordingly, the moment of inertia for this portion of the stroke

will have a given value. When, however, the main pendulum 7 swings from its normally biased position in the clockwise direction and return, the auxiliary pendulum then swings away from pendulum 7 in a manner to increase the distance between its center of gravity and the rotational axis of pendulum 7, so that the moment of inertia of the resulting combination is caused to have a value larger than the said given value. Accordingly, the period of the pendulum during this clockwise portion of the stroke is increased so that a greater time is consumed by the pendulum for completing this portion of the stroke than would be the case if the auxiliary pendulum 30 were not provided. It follows that by properly proportioning the parts, the time interval required for the pendulum combination to travel from the given position at which the contacts make and break (which position is slightly beyond the pendant position), to either of its extreme positions can be made substantially equal, thereby causing the two sets of contacts to be closed for substantially equal intervals of time.

An alternative form of the pendulum combination that may be employed in relay R is represented in Figs. 7, 8 and 9. This alternative form comprises an evacuated bulb or envelope 35 partially filled either with a liquid 37 of relatively heavy mass, such as mercury or with some other readily shiftable mass. The tube 35 is secured to pendulum 7 at a preselected point either above or below its axis of rotation but the tube is adjusted as shown in Fig. 7 to cause the mercury to gather at one end of the tube when the pendulum combination is in its pendant position. When pendulum 7 is in the counter-clockwise portion of its stroke, the mercury mass remains substantially unshifted from this position with respect to the vertical axis of the combination (see Fig. 8), hence the moment of inertia of such combination will remain substantially constant during this portion of the pendulum stroke. When, however, pendulum 7 swings in the opposite or clockwise direction, tube 35 will tilt in such a manner as to cause the mercury contained therein to flow in the other end of the tube away from the vertical axis of the combination (see Fig. 9), thereby altering the moment of inertia and hence the period of the pendulum combination. This arrangement obviously may be suitably proportioned by the proper selection of masses and distances to cause the pendulum combination to require substantially equal intervals of time to swing from just past its dead center position, at the point where the one set of contacts will break and the other set of contacts will make, to either extreme position. It follows that this arrangement will be effective to prevent a limping operation of the two sets of contacts that are asymmetrically arranged.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a pendulum, means for causing said pendulum to oscillate between two extreme positions, and a movable mass secured to said pendulum for displacement of its center

of gravity with respect to the rotational axis of said pendulum when it is intermediate its gravity biased position and one extreme position but not the other, thereby to provide a pendulum combination having a moment of inertia in one portion of its stroke that differs from the moment of inertia in another portion of the stroke.

2. In combination, a pendulum, means for causing said pendulum to oscillate at substantially its natural period, and means for varying said natural period in a selected portion of said pendulum stroke, said means comprising a weight mounted on said pendulum for displacement of its center of gravity with respect to the rotational axis thereof in said selected pendulum stroke portion.

3. In combination, a pendulum, motor means for causing said pendulum to oscillate with a predetermined amplitude at a preselected frequency, a second pendulum secured to the first pendulum for swinging movement relative thereto at a point removed from the axis of rotation of said first pendulum, and a stop on said first pendulum for limiting the swinging movement of said second pendulum to a selected portion only of the stroke of said first pendulum.

4. In combination, a pendulum, motor means for causing said pendulum to oscillate with a predetermined amplitude at a preselected frequency, two contacts operated by said pendulum and adjusted so that one contact is closed in one portion and the other contact is closed in another portion of the pendulum stroke, a movable weight secured to said pendulum at a point removed from its axis of rotation, and means for limiting movement of said movable weight in said one portion but not said other portion of the pendulum stroke.

5. In combination, a pendulum, motor means for causing said pendulum to oscillate with a predetermined amplitude at a preselected frequency, two contacts operated by said pendulum and adjusted so that one contact is closed in one portion and the other contact is closed in another portion of the pendulum stroke, an auxiliary pendulum journaled on said first pendulum at a point removed from the axis of rotation of said first pendulum, and a stop secured to said first pendulum for restraining movement of said auxiliary pendulum in a selected one of the portions of said first pendulum stroke.

6. In combination, a pendulum, motor means for causing said pendulum to oscillate with a predetermined amplitude at a preselected frequency, two contacts operated by said pendulum and adjusted so that one contact is closed in one portion and the other contact is closed in another portion of the pendulum stroke, and an envelope partially filled with a relatively heavy liquid secured to said pendulum at a point removed from its axis of rotation and adjusted to cause said liquid to flow away from the vertical axis of said pendulum in but a selected one of said portions of said pendulum stroke.

7. In a flasher relay comprising a pendulum, motor means for causing said pendulum to oscillate with a predetermined amplitude, and contacts operatively connected with said pendulum for closure of certain contacts in one portion and other contacts in another portion of the stroke of said pendulum, the combination with said pendulum of a shiftable weight operatively connected with said pendulum for displacement of the center of gravity of said weight with respect to the axis of rotation of said pendulum in a selected one of said portions of the pendulum stroke to

provide different moments of inertia of said pendulum-weight combination in said two portions of said pendulum stroke.

3. In a flasher relay comprising a pendulum, motor means for causing oscillation of said pendulum with a predetermined amplitude, two contacts operatively associated with said pendulum, one of which is closed during the portion of said pendulum stroke that extends from one extreme pendulum position to a given position which is beyond the gravity biased position and the other of which is closed during the remaining portion of said pendulum stroke that extends from the other extreme pendulum position to said given position; the combination with said pendulum of a shiftable weight operatively connected with said pendulum at a point removed from its axis of rotation for displacement of the center of gravity of said weight with respect to said axis in but said remaining portion of said pendulum stroke, whereby to provide a greater moment of inertia for said pendulum-weight combination in said remaining portion of said stroke as compared with the moment of inertia of said pendulum-weight combination in said one portion of said stroke.

9. A flasher relay comprising a pendulum, motor means for causing oscillation of said pendulum with a predetermined amplitude, two contacts operatively connected with said pendulum and asymmetrically adjusted so that one contact is closed in the portion of the pendulum stroke that extends from one extreme position to a given position beyond the gravity biased position and the other contact is closed in the remaining portion of said stroke, and a shiftable weight operated by said pendulum in such manner as to provide a moment of inertia for said pendulum-weight combination in said remaining stroke portion which is greater than the moment of inertia of said pendulum-weight combination in said first-mentioned portion of said stroke.

10. A flasher relay comprising a pendulum,

motor means for causing oscillation of said pendulum with a predetermined amplitude, asymmetrically adjusted contacts operatively connected with said pendulum and comprising a contact closed in a selected portion of the pendulum stroke that extends between one of the extreme positions of said pendulum to a given point beyond the gravity biased pendulum position and another contact closed in the remaining portion of said stroke, an auxiliary pendulum journaled to said first pendulum at a point removed from the axis of rotation of said first pendulum, and means for limiting the swinging movement of said auxiliary pendulum to the one portion of said pendulum stroke that extends between the other of said extreme pendulum positions and said gravity biased position, thereby to provide a resultant moment of inertia for said pendulum combination having a greater value in said one portion than in the remainder of the pendulum stroke.

11. A flasher relay comprising a pendulum, motor means for causing oscillation of said pendulum with a predetermined amplitude, asymmetrically adjusted contacts operatively connected with said pendulum and comprising a contact closed in a selected portion of the pendulum stroke that extends between one of the extreme positions of said pendulum to a given point beyond the gravity biased pendulum position and another contact closed in the remaining portion of said stroke, a container secured to said pendulum, and a movable weight partially filling said container, said container being adjusted to limit the movement of said weight to the one portion of said pendulum stroke that extends between the other of said extreme pendulum positions and said gravity biased position, thereby to provide a resultant moment of inertia for said pendulum combination having a greater value in said one portion than in the remainder of the pendulum stroke.

BENJAMIN MISHELEVICH.
